UNITED STATES PATENT OFFICE.

AUGUST ROHBECK, OF BELLINGHAM, WASHINGTON.

WIND-OPERATED INDICATING DEVICE.

1,116,846.

Specification of Letters Patent.

Patented Nov. 10, 1914.

Application filed April 1, 1914. Serial No. 828,922.

To all whom it may concern:

Be it known that I, AUGUST ROHBECK, a citizen of the United States, and resident of Bellingham, Whatcom county, Washington, have invented certain new and useful Improvements in Wind-Operated Indicating Devices, of which the following is a specification.

My invention consists of a mechanism, such as a wheel or like member which is acted upon by the wind so as to be thereby turned, and means whereby the movements given said wheel act to indicate or select certain characters which are combined in the order of their selection to produce written text.

The object of my invention is to produce means whereby impulses of the wind may be used to determine the selection and sequence of characters, as letters, numbers, etc.

The scope of my invention will be defined by the claims which terminate this specification.

In the drawings I have shown my invention in its preferred construction.

Figure 1 is an elevation, or side view. Fig. 2 is a plan view of the selecting and printing disk and of the indicating pointer.

The operating member of this device is a wheel or analogous construction which is mounted so as to turn freely and where it may be acted upon by the wind. As shown in Fig. 1, this consists of a shaft 1 to which are fixed cross vanes 2, which are in the form of keys. It is not intended that these be placed in angular positions which would be analogous to that of the blades of a wind wheel, that is, so that the wind will turn it continuously in the same direction.

On the contrary, it is designed that the vanes be so placed that the movements given it by the wind be of a fitful and variable character, both in amount and direction of turning. It is intended that it be subject and responsive to the fitful influences of the wind, as fully as possible. I have shown an open casing or frame 3 as inclosing the vanes. This has openings of such size as to permit free access of the wind to the vanes.

Secured to the shaft 1 is a pointer 4 which moves as does the vanes. Associated with the pointer are a set of characters, which would usually be letters or numbers, these being distributed about a circle which is concentric with the pivot axis of the pointer

4. Preferably these are letters 5, which are distributed about the edge of a disk 6. The outer edge of this disk is connected by wire stays 12 with a central ring 13. Preferably types of printing characters 7, of a like kind are placed on the lower side of the disk so that these characters may be transferred to or impressed upon a sheet of paper. For convenience in printing these characters the disk 6 is made manually rotatable about the shaft 1, so that all characters may be brought to a fixed printing position. It is made movable vertically, in order to thus print the characters, by yieldingly supporting it, as by springs 8, which support it from the paper carrying table, 9. These types or printing characters may be inked by use of an ink pad, or by using an inked ribbon, as shown at 11. The paper 10 is shown beneath the ribbon in Fig. 1. To insure printing of only the one character designed, a slightly raised table 90 is provided beneath the ribbon at the point where the printing is done.

In using this device, the wind will swing the pointer from one position to another, causing it to stop at widely varying positions. When the pointer stops, the disk 6 is turned to bring the character indicated by the pointer to the printing position and the character printed upon a sheet of paper by depressing it thereon. This operation follows each change in position of the pointer, thus assembling letters in order, the printed sheet being then examined to discover what, if any, intelligible meaning may be found therein.

What I claim as my invention and desire to patent is:

1. A wind controlled indicating device comprising a wind-turned member, a pointer connected to be turned by said member, and a disk mounted to be turned independently of and about the same axis as said pointer and carrying typographic characters about its edge.

2. A wind controlled printing device comprising a vertical rotative shaft, arms in the form of keys carried by one end of said shaft and extending transversely thereof to form a wind wheel, a pointer secured to the other end of said shaft, a disk carrying typographic characters about its edge and mounted to be turned concentric with the shaft and also to be shifted to press down

its edge, and means for printing from said characters by said movement of the disk.

3. A wind controlled printing device comprising a vertical rotative shaft, arms in the form of keys carried by one end of said shaft and extending transversely thereof to form a wind wheel, a pointer secured to the other end of said shaft, a disk carrying typographic characters about its edge and 10 mounted to be turned concentric with the shaft and also to be shifted to press down its edge, a paper holding table beneath said disk and means for inking said characters to print therefrom.
- 15 4. A wind controlled printing mechanism comprising a revoluble shaft, a wind wheel secured thereto, a casing inclosing said wheel

and having openings for the passage of the wind therethrough, a pointer secured to said shaft, a disk having printing characters about its edge and facing downwardly, said disk being mounted concentric to the shaft and to be manually turnable, a paper holding plane extending beneath said disk and springs supporting said disk a slight distance above the paper holding plane.

In testimony whereof I have hereunto affixed my signature this 25th day of March, 1914.

AUGUST ROHBECK.
